CLAIM

The ornamental design for a sensor for golf having indicating image design displayed thereon, as shown and described.

DESCRIPTION

FIG. 1 is a front perspective view of a sensor for golf having indicating image design displayed thereon according to the present design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

(Continued)

The broken lines showing of parts of the drawings are for the purpose of illustrating environmental structure and form no part of the claimed design.
